UNITED STATES PATENT OFFICE.

THOMAS F. FARRELL, OF PATERSON, NEW JERSEY.

STEAM ROCK-DRILL.

SPECIFICATION forming part of Letters Patent No. 390,578, dated October 2, 1888.

Application filed March 8, 1888. Serial No. 266,507. (No model.)

To all whom it may concern:

Be it known that I, THOMAS F. FARRELL, a citizen of the United States, residing at Paterson, in the county of Passaic and State of New Jersey, have invented new and useful Improvements in Steam Rock-Drills, of which the following is a specification.

This invention relates to an improvement in drills, and by means of this invention the construction of the actuating mechanism for the drill is simplified, as set forth in the following specification and claims, and illustrated in the accompanying drawings, in which—

Figure 1 is a central longitudinal section of mechanism for actuating a drill. Fig. 2 is a section in the plane $x'x$, Fig. 1. Fig. 3 is a section in the plane $y'y$, Fig. 1. Fig. 4 is a section in the plane $z'z$, Fig. 2. Fig. 5 is a section in the plane $x'x'$, Fig. 1.

Similar letters indicate corresponding parts.

In the drawings, the letter A indicates a cylinder, and B is a piston having the ends C D. The steam-chest E has a supply-pipe, F, and a valve having the heads G H I J is placed in the chest E. When the parts are in the position shown in Fig. 1, the steam passes from the supply-pipe F into the steam-chest E and between the valve-heads I J through the port K, and said steam pressing on the piston end D moves the piston in the direction of the arrow 1 on said piston in Fig. 1. When the piston B has traveled to the limit of its path in the direction of arrow 1, the head D has passed the duct N, and the steam from the port K,

entering through the duct N into the steam-chest E, presses on the valve-head G and moves the valve so as to cut off the communication between the supply-pipe F and the duct K, and to allow the steam from the supply-pipe F to pass between the valve-heads G H to the port L. The steam issuing from the port L presses on the piston end C and moves the piston in the direction opposed to that of the arrow 1. This return motion of the piston continues until the piston has reached the position shown in Fig. 1, when the piston-head C has passed the duct O, so that steam from the port L will pass through the duct O and will press on the valve-head J, thus moving the valve back to the position shown in Fig. 1, when the piston again moves in the direction of arrow 1.

An outlet, P, enables any steam that may

be confined between the piston ends C D to pass to the exhaust M.

The piston B is tapped for the reception of 55 a screw-shank, Q. On said shank Q is firmly mounted a toothed wheel, R. The detent S is provided with a head, T, and a channel, U, leads from the cylinder A to the detent-head T. When the piston is moving in the direction of arrow 1, the steam from the port K, passing through the channel U, presses on the detent-head T and moves the detent S against the resistance of the spring V, so that the detent S engages the toothed wheel R and prevents said wheel, with the screw-shank Q, from rotating. The result is that the piston B, while moving in the direction of arrow 1, rotates about the screw-shank Q, thus imparting a longitudinal and a rotary motion to the rod W. 70 When the piston B moves in the direction opposed to that of arrow 1, the steam-pressure on the detent-head T is removed, so that the spring V moves the detent S out of engagement with the toothed wheel R, leaving said wheel with 75 the screw-shank Q free to rotate. The result is that during the motion of the piston in the direction opposed to that of arrow 1 the screw-shank Q and wheel R rotate, while the piston B moves longitudinally without rotating.

The piston-rod W is made to pass through the head X, having a recess containing the split or sectional rings Y. Screws Z are inserted laterally into the head X, and are made to press the rings Y tightly about the rod W, so 85 as to form a stuffing-box.

The ports K L, as seen in Figs. 2 and 3, are made to cross one another—that is to say, the port K leads to that part of the cylinder which is near the piston end D and the port L leads 90 to that part of the cylinder which is near the piston end C. By locating the ports K L at the side of the cylinder, as shown, said ports can be readily made to clear the ducts N O and the outlet P, thus making the casting of 95 the ports K L and outlet P easy and simple.

By having the ports K L crossed, as shown, the stroke of the piston is shortened, since the piston will only travel in the direction of arrow 1 until the end D has passed the duct N, and 100 said piston will only travel in the direction opposed to arrow 1 until the end C has passed the duct O.

Another advantage of having the ports K L

at the side is that in drilling or forming the ducts N O and outlet P the ports K L do not have their walls perforated or injured, thus avoiding the bushing which is required in case 5 the walls are perforated.

What I claim as new, and desire to secure by Letters Patent, is—

1. The combination, with the cylinder, the piston, the valve-heads G H I J, and the valve-chest, of the ducts N O, the outlet P, and the two ports K L, extending, respectively, along the opposite sides of the cylinder, with their inner end-portions extending beyond or past each other and opening into the chest, substantially as shown and described. 15

2. The combination, with the cylinder, the piston, the valve, the steam-chest, and ports

communicating with the chest and cylinder, of a screw extending into and engaging the piston and having a toothed wheel, R, and a detent moved by the pressure of steam from the piston-cylinder to lock and hold the toothed wheel stationary as the piston moves in one direction and relieved of steam-pressure to release the wheel when the piston moves in the opposite direction, substantially as described. 25

In testimony whereof I have hereunto set my hand and seal in the presence of two subscribing witnesses.
